(57) **CLAIM**

The ornamental design for a mop, as shown and described.

DESCRIPTION

FIG. 1 is a front, right, and top perspective view of a mop, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a handle; and,

FIG. 10 is a partial enlarged view of an area labeled 10 in FIG. 2 comprising a mop head.

The evenly-spaced broken lines depict portions of the mop that form no part of the claimed design.

The dot-dash line shown in FIGS. 1, 2, 9, and 10 framing portions of the mop for enlargement purposes forms no part of the claimed design.

The mop includes a symbolic break along its length drawn in dot-dot-dash broken break lines.

The dot-dot-dash broken break lines and the area between the break lines in FIGS. 1-6 form no part of the claimed design.
